UNITED STATES PATENT OFFICE.

CONSTANT EUGÈNE LAMOISE, OF NAMUR, QUEBEC, CANADA.

POST-DRIVING APPARATUS.

1,387,894.

Specification of Letters Patent. Patented Aug. 16, 1921.

Application filed January 27, 1921. Serial No. 440,416.

To all whom it may concern:

Be it known that I, CONSTANT EUGÈNE LAMOISE, subject of the King of Great Britain, residing at Namur, Labelle county, 5 Province of Quebec, Canada, have invented certain new and useful Improvements in Post-Driving Apparatus, and do hereby declare that the following is a full, clear, and exact description of the invention, such 10 as will enable others skilled in the art to which it appertains to make and use the same.

The present invention relates to new and useful improvements in post driving apparatus.

The primary object of the invention is the provision of a post driving apparatus in which the body portion or platform thereof may be maintained in a horizontal position, 20 no matter how uneven the ground upon which the same is operating, may be.

Another object of the invention is the provision of means for adjusting the said platform laterally with respect to its 25 wheeled frame, and also for adjusting the post driving means longitudinally of the frame.

Still another object of the invention is the provision of means for tilting the platform, 30 laterally relative to its wheeled supporting frame, and retaining the said platform in such tilted position, to prevent any undesired movement.

A further object of the invention, is the 35 provision of means controlled by an operating crank, for tilting the post driving means, which is pivotally connected to the platform longitudinally relative to said platform and wheeled supporting frame, for 40 adjusting the apparatus with respect to the irregularity of the ground.

A further object of the invention, is the provision of means, for simultaneously raising 45 one side of the platform or body of the device and lowering the other, to conform to the unevenness of the ground.

A still further object of the invention is the provision of a post driving apparatus which will be comparatively simple and inexpensive to manufacture, reliable and efficient in use, and readily operated.

With the above and other objects in view, the present invention resides in the novel features of construction, formation, combination, and arrangement of parts, to be

hereinafter more fully described, claimed and illustrated in the accompanying drawings, forming a part of the present application, and in which:

Figure 1 is a perspective view of a portion of the invention;

Fig. 2 is a side elevation thereof;

Fig. 3 is a top plan view thereof;

Fig. 4 is an end view thereof;

Fig. 5 is a detail sectional view, through one of the adjusting pulleys; and,

Fig. 6 is a plan view, of the journal for the said pulley.

Referring now to the accompanying drawings, by corresponding characters of reference throughout the several views the numeral 10 designates in general my improved apparatus which consists of a wheeled frame, 11 including opposite front and rear bolsters 12 and 13, of triangular formation 75 and to the apexes of which are pivotally mounted as at 14, a base or platform 15.

A motor shown at 16 is mounted at the rear end of the platform 15, while intermediate the ends thereof is a transverse frame 16', in which are journaled the upper and lower shafts 17 and 18.

The shafts 17 and 18 may be rotated by means of the cranks 20 and 21 respectively, while a pulley 22 is keyed to the shaft 18 85 and is operated by belts 23 which pass over a pulley 24 driven by the motor 16.

The post driving apparatus is shown by the numeral 25 and consists of a pair of guide bars 26, in which a weight 27, designed to strike the post and drive it into the ground is mounted.

The weight 27 has cable 28 attached thereto, which passes over a pulley 29 journaled between the upper end of the bar 26. This 95 cable passes over a pulley 30 secured to the forward end of the platform 15, and is attached at its opposite end to a drum 31 which is loosely mounted upon the shaft 19 but is adapted to be driven thereby by the 100 clutch element 32, which is operated by a hand lever 33.

Normally the drum 31 is loosely mounted upon the shaft 19 so that the operation of the pulley 22 has no effect upon the same. 105 By operating the lever 33 the clutch 32 may be thrown into engagement with the drum 31 and the same rotated to raise the weight 27 to the upper end of the post driving device 25, at which point, it may be 110

released by means of the clutch 32 through the medium of the hand lever 33 and will fall, striking the post, driving it into the ground.

5 In order to provide for the movement of the post driving mechanism 25 in its vertical relations to the platform 15 to agree with the unevenness of the ground, a pair of rods 34 are threaded in the block 35 which are 10 attached to the opposite side bars 26.

The opposite ends of these rods 34 are provided with pinions 36 which mesh with corresponding pinions 37 keyed to the before mentioned shaft 17 and obviously upon 15 the rotation of the crank 20 in opposite direction, the upper ends of the bars 26 will be moved outwardly or inwardly as desired, so that the device 25 will be at all times maintained in a proper vertical position 20 with respect to the machine.

Rods 38 and 39 are secured to the outer ends of each of the bolsters 12 and 13 and are provided with oppositely inclined screw threads 40 and 41 at their upper ends.

25 Sprocket wheels 42 and 43 are threaded on the upper ends of the rods 38 and 39 respectively and are provided with depending sleeves 44 which fit within the bearings 45 pivotally mounted as shown at 46 on the 30 opposite sides of the platform 15 adjacent the ends thereof. The rods 38 and 39 pass upwardly through these bearings through the sprocket wheels above referred to. Vertical counter shafts 47 are mounted on the 35 frame 16 and carry gears 48 at their upper ends which mesh with the gears 49 keyed to the before described shaft 18. Obviously upon the rotation of the cranks 21 the shafts 47 will be rotated.

40 Sprocket wheels 50 are keyed to the lower end of the shafts 47 and over the same pass chains 51 and 52 which engage the before described sprocket wheels 42 and 43 and upon the rotation of the shaft, drive these 45 sprocket wheels in such manner, that the body will be tilted either to the right or to the left as desired to agree to the unevenness of the ground.

From the foregoing it will be readily seen 50 that the lateral adjustment of the platform 15 together with the longitudinal adjustment of the driving mechanism 25, relative to the platform, will be such that the said driving mechanism will be at all times 55 maintained in a vertical position for properly driving the posts in the ground.

The frame 10 may be provided with suitable wheels 53 by means of which the device can be transported from one locality to another as desired.

From the foregoing description taken in connection with the accompanying drawings it will be manifest that a fence post driving apparatus, is provided which will fulfil all 65 of the necessary requirements of such a de-

vice, and it should be understood in this connection, that various minor changes in the specific details of construction can be resorted to within the scope of the appended claims without departing from the spirit or 70 sacrificing any of the advantages of the invention.

Having thus fully described my invention, what I claim as new and desire to secure by Letters Patent is:—

1. A machine of the character described including a wheeled frame, bolsters at the end of said wheeled frame, a platform pivoted at its ends to the upper ends of said bolsters for tilting movement thereon, threaded rods secured to the bolsters, guides carried by the opposite sides of the platform for receiving said rods, said guides having openings with curved surfaces formed therein, sprockets threaded upon the said rods, extensions on the sprockets and fitting in the said openings, means for rotating said sprockets in opposite directions upon opposite sides of the frame, and tilting the platform laterally relative to the frame, a driving apparatus mounted upon said frame, and means for tilting the driving apparatus longitudinally relative to the frame.

2. A machine of the character described including a frame, a platform mounted at 95 its ends upon said frame to tilt laterally thereof, threaded rods carried by the frame and passing through the guides secured to the platform, sprockets threaded upon said rods, extensions on the sprockets and fitted 100 in openings formed in said guides, means for rotating the sprockets upon opposite sides of the frame, in opposite directions simultaneously and tilting the platform in 105 opposite directions relative to the frame, a driving apparatus pivoted to one end of the frame, threaded rods passing through said apparatus and means for rotating said threaded rods, and tilting the driving apparatus relative to the frame.

3. A machine of the character described including a tilting platform, a plurality of shafts located upon said platform, means for rotating said shafts, means operatively connected with said shafts to tilt said platform in one direction, a driving apparatus mounted upon said platform, a means for tilting the driving apparatus in an opposite direction to the platform, whereby said driving apparatus will at all times be maintained in a vertical position.

4. A device of the character described including a tilting platform, a frame mounted thereon, shafts mounted in said frame, threaded rods passing through the ends of 115 said platform, sprockets threaded upon said rods, and engaging the guides in which the rods are mounted, means operatively connecting the sprockets and one of the shafts 120 for rotating the sprockets upon opposite 125

sides of the frame in opposite directions and tilting the platforms in one direction, a driving apparatus mounted upon said frame to tilt in an opposite direction from the platform, a pair of threaded rods engaging the driving apparatus, and means for operatively connecting the threaded rods, with one of said shafts, for tilting the

driving apparatus in an opposite direction to the tilting of the platform.

In witness whereof I have hereunto set my hand.

CONSTANT EUGÈNE LAMOISE.
